VEHICLE SIGN

Fred E. Brazie, 7217 Douglas, Des Moines, Iowa

Filed June 14, 1965, Ser. No. 85,705

Term of patent 14 years

(Cl. D1—12)

FIG. 1 is a rear perspective view of a vehicle sign embodying my new design;

FIG. 2 is a front view thereof,

FIG. 3 is a rear view thereof,

FIG. 4 is a top view thereof,

FIG. 5 is a bottom view thereof, and

FIG. 6 is a side view thereof.

The dominant features of my design reside in the portions shown in full lines, it being understood that the broken line representation of a vehicle hood in FIGURE 1 is for purposes of illustration only.

I claim:

The ornamental design for a vehicle sign, as shown, and described.
